STRUCTURAL UNIT

Milton E. C. Klose, Manitowoc, Wis.; Helen Klose
administratrix of said Milton E. C. Klose, deceased

Application February 26, 1949, Serial No. 78,528

7 Claims. (Cl. 20—91)

1

This invention relates to an improved structural unit for use in doors, partitions, panels, and the like.

Inasmuch as the unit is particularly adapted for use in doors, the invention will be described in detail with reference to a panel door construction. However, it will be understood that the unit is also adapted for other analogous or related structural uses such as in wall panels or partitions, aircraft, boats, and furniture.

Hollow panel constructions comprising a wood frame with plywood facing members glued to opposite sides thereof are used extensively in the structural arts because of their decided advantages over metal or solid wood panels. Hollow panels of this character are strong, durable, and relatively light in weight and have superior insulating properties with respect to the transmission of heat and sound. Furthermore, such constructions are more economical to manufacture, handle, and transport.

The hollow interior of such a panel may be provided with a cellular core or filler comprising usually a grid of interconnected cross-pieces such as wood bars or strips. A reinforcing filler of this type increases the strength and durability of the door and, dependent upon the nature of the filler, may also assist in resisting the detrimental effects of warpage and shrinkage which tend to occur as a result of the varying percentages of moisture absorbed by the wood under exposure to air of varying moisture content. In order to further minimize or avoid warping and undesirable deformation of the door, it has been proposed to provide ventilating holes or other apertures in the frame and throughout the filler whereby to permit free passage of air and moisture between the interior of the panel and the outside atmosphere.

I have found that, although it is desirable to employ a reinforcing filler or core in the interior of the hollow panel for imparting greater strength to the panel and for resisting the high pressures ordinarily employed during gluing of the plywood facings to the frame, yet the internal grids and other filler arrangements previously proposed are subject to serious disadvantages in many cases. Thus, where the filler comprises a plurality of cross-strips interconnected to form a relatively rigid grid, the resultant door construction is often so rigid and non-flexible that extreme care must be exercised to insure that the door casing or other cooperating structure is in exact alignment with the door. If the internal grid comprising interconnected filler

2

elements is also attached or secured to the frame comprising part of the door structure, the rigidity of the door is further increased.

Such extreme rigidity is undesirable in many applications of this type of structural unit. For example, in the manufacture of cabinets for use in laboratories, offices, stores, and homes, sliding doors of the flush panel type construction hereinbefore described are commonly employed. These doors are slidably mounted in elongated grooves or tracks secured to the door casings or other portions of the cabinet on either side of the doors. If the door is of such rigid and non-resilient construction as to preclude even a minor degree of flexing, it will be seen that the slide tracks must be in exact alignment with each other or with the edges of the door in order to avoid binding and insure easy sliding operation of the door.

Accordingly, the general object of my invention is to provide a structural unit of the class described which possesses the required structural strength and resistance to warpage but which is also characterized by a certain degree of elasticity and resiliency permitting limited flexing of the unit during use thereof.

A further object of the invention is to provide a hollow panel door structure in which the door is sufficiently resilient to conform under relatively slight pressure to a misaligned door casing or other cooperating structure.

Another object of the invention is to provide a structural unit of the class described which contains a plurality of independent filler elements having no rigid connections with each other or with the frame.

Another object of the invention is to provide a structural unit of the class described in which a plurality of independent filler elements are retained in predetermined spaced arrangement during assembly of the unit.

Still another object of the invention is to provide, in a structural unit of the class described, novel means for internally ventilating the unit including a plurality of independent spaced filler elements in the interior of the unit and an opening through the frame which comprises part of a joint structure of the frame.

Other objects and advantages of the invention will become apparent from the subsequent detailed description of the invention and the accompanying drawings, in which:

Fig. 1 is an elevational view of a panel door comprising one embodiment of my invention;

Fig. 2 is an enlarged fragmentary view of the

upper left hand corner of the door shown in Fig. 1, portions of the front facing being broken away to show the internal construction of the door;

Fig. 3 is an enlarged perspective view of a filler element, of the type employed in Figs. 1 and 2, illustrating the manner in which the element is attached to a positioning means comprising wire netting;

Fig. 4 is a fragmentary elevational view of a corner of the door showing one method by which the frame members may be secured together;

Fig. 5 is an edge view looking downwardly along the lines 5—5 of Fig. 4;

Fig. 6 is a fragmentary elevational view similar to Fig. 4 but showing a modified method of joining the frame members;

Fig. 7 is a fragmentary elevational view similar to Figs. 4 and 6 but showing still another method of joining the frame members;

Fig. 8 is an enlarged fragmentary view similar to Fig. 2 but showing a filler assembly employing a different type of filler element;

Fig. 9 is an enlarged top plan view of a filler element of the type seen in Fig. 8; and

Fig. 10 is a cross-sectional view of the filler element taken along the lines 10—10 of Fig. 9.

Referring first to Figs. 1 to 3, inclusive, the door structure shown therein for purposes of illustrating one specific embodiment of my invention comprises a pair of elongated wood stiles 16 connected by means of a pair of upper and lower wood rails 17 to form a frame indicated generally at 18. Secured to opposite sides of the frame 18 are plywood facings or panel members 19 each consisting of a plurality of plies. In the case illustrated three plies are shown. Relatively thin metal panel members may also be used if desired. The panel members 19 are preferably secured to the frame 18 by means of glue or other suitable adhesive material, as hereinafter described. A pair of mounting blocks 21 are secured to the inner side of each of the stiles 16 in order to facilitate the mounting of locks or other hardware.

Disposed within the interior space enclosed by the frame 18 and the panel members 19 is a filler assembly or core comprising a plurality of independent elongated rectangular wood blocks 22. These blocks are distributed in predetermined spaced relationship throughout the space between the panel members 19, the blocks having the same thickness as the frame 18. As seen in Fig. 2, the blocks 22 are preferably arranged in laterally spaced rows with the blocks staggered both horizontally and vertically and with the opposite ends of each block in each row extending slightly beyond the ends of the blocks in adjacent rows. This overlapping relationship of the blocks 22 eliminates vertical lines of potential weakness which might be present if the ends of the blocks were aligned. The elongated blocks 22 are also preferably arranged so that the long dimension of each block extends generally parallel to the short dimension of the door, thereby further increasing the strength of the door.

In order to provide maximum structural strength and resistance to the effects of warpage of the wood, the blocks 22 have their grain running lengthwise therein and the innermost ply, indicated at 23 in Fig. 2, of each of the panel members 19 is disposed with its grain running at substantially right angles to the grain of the blocks 22. Each of the succeeding plies, indicated at 24 and 26, respectively, have their grains run-

ning at substantially right angles to the grain of the adjacent plies.

As hereinbefore referred to, an important feature of my invention resides in the fact that the blocks 22 are completely independent and have no rigid connections with each other or with the frame 18. The blocks 22 are rigidly secured, preferably by glue, on opposite sides thereof only to the inner faces of the panel members 19. By thus employing a core composed of completely independent and unattached filler elements distributed in predetermined arrangement to impart maximum structural strength to the unit, I obtain a door construction which will still permit a limited degree of flexing or planar distortion in order to conform to any slight misalignment or misshaping of the door casing or other surrounding structure which cooperates with the door during its use.

In order to facilitate the positioning of the blocks 22 in the desired spaced arrangement, based upon considerations of structural strength, and in order to retain the blocks in the desired arrangement during assembly of the unit, I employ a positioning means which in this instance (Figs. 1 to 3) comprises a section of wire mesh or netting 27 cut to fit snugly within the frame 18. The netting 27 may conveniently comprise ordinary galvanized chicken wire or poultry netting although, of course, other types of netting or mesh fabric having similar properties may also be employed. Each of the elongated blocks 22 is provided with grooves in the form of a pair of spaced transverse slots or incisions 28 (Fig. 3), the slots being engageable with adjacent strands of the wire netting 27 to retain each of the blocks in position on the netting. The slots 28 are relatively narrow in order to frictionally engage the wire strands and are preferably adapted to receive relatively thicker strands of the netting such as the portions indicated at 29 (Fig. 3) and comprising two adjacent wire strands twisted together. The section of netting 27 may be inserted within the frame 18 with its edges merely in abutment or frictional engagement with the inside of the frame, or, if desired, the netting may be secured to the frame.

In assembling a door construction of this character, the inner face of one of the panel members 19 may first be coated with glue or other suitable adhesive and the frame 18 is then mounted against the glue-coated side of the panel member with the edges of the panel member and the frame in flush relationship. A section of wire poultry netting 27 is cut to the size required to fit within the frame 18. The blocks 22 are then attached to the piece of netting 27 by means of the slots 28, the blocks 22 preferably being arranged in rows on the netting as seen in Fig. 2, with the blocks staggered horizontally and vertically, with opposite ends of each block in overlapping relationship with the ends of the blocks in adjacent rows, and with the longitudinal grain of the blocks running at right angles to the grain of the innermost ply of the panel member 19 in the manner hereinbefore described. The section of netting 27 with the blocks 22 attached thereto is placed within the frame 18 with the blocks in contact with the glue-coated surface of the panel member 19. A second panel member is then coated with glue and mounted on the opposite side of the frame in contact with the frame and blocks and with the grain of the innermost ply of the panel member also running at right angles to the longitudinal grain

of the blocks. During the mounting and positioning of the second panel member, the wire netting 27 serves to hold the blocks 22 against shifting or displacement thereby positively retaining the blocks in the desired spaced relationship within the frame. The assembled structure is then dried under pressure such as in a hydraulic press. It will be understood that instead of coating the panels 19 with glue, the frame 18 and blocks 22 may be coated with glue and the panels applied thereto as before.

Figs. 4 to 7, inclusive, illustrate several alternative methods of joining together the stiles 16 and the rails 17 which together comprise the frame 18. In Figs. 4 and 5 the stile 16 is provided with a mortise 30 and the rail 17 is provided with a complementary tenon 31 arranged to fit securely within the mortise 30. The mortise 30 is overcut both transversely and longitudinally of the stile 16 whereby to provide a ventilating aperture 32 communicating between the interior of the frame 18 and the outside atmosphere. Thus, by means of the ventilating aperture comprising the overcut mortise 30 and the completely independent and spaced relationship of the filler blocks 22, my invention provides for free circulation of air and moisture between the interior of the door and the outside atmosphere. Figs. 6 and 7 illustrate slightly different methods of joining the stiles 16 to the rails 17. In Fig. 6 the stile 16 and the rail 17 abut at right angles and are secured by means of a pair of corrugated metal fastening elements 33. In this instance a ventilating hole 34 is provided through the rail 17. In Fig. 7 the ends of the stile 16 and the rail 17 are mitered to provide for angular abutment, the two members also being secured by means of corrugated fasteners 33 or other similar devices. In this form the rail 17 is also provided with a ventilating hole 34.

Referring to Figs. 8 to 10, inclusive, there is illustrated a different form of wood filler block for use in conjunction with a wire netting in the same general manner as shown in Figs. 1 to 3. In this form of the invention the filler element comprises a cylindrical wood block 36 having a hollow interior 37. The axial height of the blocks 36 is, of course, the same as the thickness of the frame 18. Each of the blocks 36 is provided with a central circumferential groove 38 for receiving and engaging the wire strands of the netting. As seen in Fig. 8, the cylindrical blocks 36 are inserted in the hexagonal openings of the wire netting 27 with the strands of wire being received in the grooved portions 38 and being distorted slightly to conform to the circular shape of the blocks 36. Each of the blocks 36 is also provided with a pair of transverse vent holes 39 extending radially from the hollow interior 37 to the outer cylindrical surface in order to permit free passage of air and moisture between the interior and exterior of the blocks. The method of assembling the unit in the case of the cylindrical blocks is generally the same as described above in connection with the elongated rectangular blocks, the panel members 19 being glued to the opposite axial ends of the cylindrical blocks 36.

As previously pointed out, the structural unit herein described has a considerable advantage over the structural units of this general type which have previously been proposed because of the complete absence of rigid connections between the individual filler elements and also between the filler elements and the frame. The

resultant structure is strong and durable yet possesses sufficient resiliency so that it may be flexed or distorted slightly to conform to adjacent cooperating structures such as a door casing or cabinet framework.

In addition, the structural unit comprising my invention also possesses other important advantages. The use of a number of small independent filler elements instead of the larger interconnected grid members heretofore employed is more economical since these small pieces may be cut from lumber which would ordinarily be wasted. Furthermore, because the filler elements are relatively small in size, the effect of changes in moisture content and warping of the filler elements is minimized. Filler elements formed from relatively wide strips of wood tend to bow or arch considerably across the short dimension thereof under warping conditions. Obviously, such bowing or arching is avoided by use of the relatively narrow, rectangular filler blocks or the cylindrical filler blocks described above. Also, where the filler elements are rigidly attached to each other, as in the grid type fillers of the prior art, the warpage and strain of each filler element is transmitted to the other elements, and the cumulative effect of such warpage may produce bowing or arching of the entire grid or filler assembly resulting in distortion of the entire door.

In many cases the use of a plurality of independent filler blocks instead of the bulky interconnected grids of the prior art results in a substantial reduction in the weight of the completed unit. Moreover, the use of a plurality of filler elements permits considerable variation in arrangement of the elements in the interior of the door to obtain different degrees of structural strength and durability dependent upon the ultimate use of the unit. I have also found that a core comprising a large number of independent filler blocks is well adapted to withstand the relatively high pressures to which structural units of this type may be subjected in many hot gluing presses.

Although the invention has been described in detail with respect to only a few specific embodiments, it will be understood that various modifications and equivalent structures may be employed without departing from the scope of the invention as defined in the appended claims.

I claim:

1. A structural unit of the class described comprising a frame, panel members secured to opposite sides of said frame, a plurality of filler elements disposed in predetermined spaced arrangement within the space enclosed by said frame and panel members, and a section of non-rigid netting within said space interengaged with said filler elements for positioning the latter in said spaced arrangement during assembly of the unit, each of said filler elements having no rigid connection with the other elements or with said frame and being rigidly secured only to said panel members.

2. A structural unit of the class described comprising a frame, panel members secured to opposite sides of said frame, and a filler assembly in the space enclosed by said frame and panel members, said filler assembly comprising a section of non-rigid netting and a plurality of independent wood blocks each disposed in engagement with the mesh of said netting whereby to position said blocks in predetermined

spaced arrangement, said blocks being rigidly secured only to said panel members.

3. The structure of claim 2 further characterized in that said blocks have an elongated rectangular shape and are arranged within said space in a plurality of rows staggered both horizontally and vertically and with the opposite ends of the blocks in each row extending beyond the ends of the blocks in adjacent rows in overlapping relation therewith.

4. The structure of claim 2 further characterized in that said blocks have an elongated shape with the grain running lengthwise therein, said panels are ply wood panels, and the innermost ply of each panel has its grain running substantially at right angles to the length of said blocks.

5. The structure of claim 2 further characterized in that said blocks have a cylindrical shape extending axially between said panel members.

6. The structure of claim 2 further characterized in that said blocks comprise hollow cylindrical blocks extending axially between said panel members and being radially apertured to permit passage of air and moisture between the outside and the hollow interior of the blocks.

7. The structure of claim 1 further characterized in that said frame is apertured for per-

mitting free circulation of air and moisture between the outside atmosphere and the interior of the unit whereby to retard warpage of the same.

5

MILTON E. C. KLOSE.
